UNITED STATES PATENT OFFICE.

GEORGE A. BELL, OF MARION, INDIANA, ASSIGNOR TO INDIANA FIBRE PRODUCTS COMPANY, OF MARION, INDIANA, A CORPORATION.

BLANK PAPER BOX OR CARTON.

Application filed July 27, 1928. Serial No. 295,698.

This invention is a folded blank paper box or carton of peculiar construction and design adapted to contain a sad iron or other article for packing and shipping.

5 The object of the invention is to enable such box or carton to be easily made by cutting or stamping out a blank and scoring the parts thereof in certain peculiar places so that the parts may be conveniently folded 10 into certain forms and united with each other readily for securely enclosing an article and for readily examining or removing the article, and the box or carton to be economical in construction and to have such 15 shape as to render it economical for packing, shipping and storage of a number of such cartons.

Said box or carton, when formed and before packing the article therein, has a body 20 portion including a vertical rectangular back, a horizontal rectangular bottom, and vertical ends tapering somewhat upwardly by being inclined along the front edges thereof and being partially reinforced and 25 overlapped by reinforcing members integral with the rear and secured to the ends between the front and rear thereof. The front portion is integral with, and therefore 30 hinged to the bottom, and adapted to be folded up against the inclined front edges of the ends of the body of the box and with lateral wings which are adapted to wedge 35 in tightly between the ends of the body of the box and their reinforcing members. The 40 top is integral with the rear part of the box and is folded over upon the tops of the ends and has end walls secured to a front strip which is inclined parallel with the front 45 edges of the ends of the box so that the top embraces tightly the front member of the 50 box and cooperates with the means for holding the wings of the front of the box tightly in connection with the body of the box, whereby the box is very strong, durable, and 55 is conveniently manipulated, and may be packed with other boxes of similar shape so as to economize space.

The full nature of the invention will be more fully understood from the accompanying drawings and the following description and claims:

In the drawings, Fig. 1 is a perspective view of said box with the top and front members open. Fig. 2 is an end elevation 55 of the box but enclosed. Fig. 3 is a horizon-

tal section through the box on the line 3—3 of Fig. 2. Fig. 4 is a plan view of the blank from which the box is formed.

The box or carton is formed from a single blank made of paper or like material, cut 60 and scored as shown in Fig. 4. Said blank consists of a bottom 10 with integral ends 11 with which the body of the box is formed when the back 12 is folded up therewith and the ends 13 of the back 12 are folded against 65 and over the ends 11 and secured rigidly thereto by fasteners 14. Thus it is seen in Fig. 1 that the ends 11 are integral with the bottom 10 and are turned upward to a vertical position by reason of the score lines 111. 70 The back 12 is integral with the bottom 10 and, by reason of the score line 112 can be folded to a vertical position, as shown in Fig. 1, against the ends 11; and the ends 13 of the back, by reason of the score lines 75 113, can be folded on the outside and against the ends 11, and the fasteners 14 are located between the front and rear edges of the ends 13 so that practically the forward half of 80 said ends 13 are free but held against the ends 11.

The front member 15 is integral with the front edge of the bottom 10 at the score line 115, but is otherwise free and it has ends 16 integral therewith at the score lines 116. 85 The front 15 is adapted to extend to the top of the ends 11 and when folded up, as shown in Fig. 2, the ends 16 of the front member may be tightly wedged in between the ends 13 of the back and the ends 11 of the bottom or body of the box or carton so as to 90 make a very tight and strong fit.

The top 17 is integral with the top of the back at the score lines 117, but otherwise free, and it has ends 18 connected with the 95 back at the score lines 118; and a front strip 19 is integral with the top 17 at the score lines 119 and has end extensions 20 which overlap the ends 18 of the top and is secured thereto by the fasteners 21, as shown. The 100 width of the top 17 from front to rear is the same as, or but slightly greater than, the width of the ends 11 at the top so that when the top is closed, as shown in Fig. 2, it will overlap and cover the upper parts 105 of the ends 11, ends 13 and ends 16 and front 15, and envelops the same so as to make a tight top closure.

The front edges 111 of the ends 11 are 110 inclined upwardly and rearwardly when

the box is formed, as shown in Fig. 1, so that the upper part of the box is narrower from front to rear than the lower end of the box, substantially as shown. Likewise, the extensions 20 of the front strip 19 of the top are located on the ends 18 of the top so that said front strip 19 will flare downwardly and outwardly somewhat as shown in Fig. 2, and thus be inclined in substantial alignment with the front 15 when closed, which inclination is caused by the inclined edges of the ends 111 of the body of the box.

The foregoing drawings and description show how, out of a single piece of paper board or the like, all parts of the box or carton, except the fasteners, are cut and folded easily into the final form as shown.

The ends of the box, when finally formed, are relatively very thick and strong and capable of resisting enormous and thrusts. The ends throughout are three or more plies in thickness. In the upper portion, the ends are four plies thick, and, in the remaining portions, three plies thick, and these plies are strongly secured in place. This renders such carton peculiarly and well adapted for packing and shipping a sad iron or like article, or an electrically heated sad iron. The end thrusts of the point of said sad iron and the legs thereof at the two ends respectfully are successfully resisted by the strong construction of the ends of the box, and particularly with the reinforcement of the enveloping top thereof.

By inclining the edges 111 of the ends 11, as shown and explained, and also the front of the top of the box, the carton is made not only to best fit the sad iron packed and shipped therein, but to reduce the size of the box or carton from front to rear so as to economize the space occupied by the carton in packing the same for shipping by reversing each alternate box or carton so

that the first box would be in the position shown in Fig. 2 and the second box would be inverted, with the wide portion uppermost and the narrow portion extending downward.

The invention claimed is:

1. A folding blank box including a bottom with integral ends extending upwardly therefrom, a back integral with the bottom and rigidly secured thereto by integral end members overlapping the ends from the bottom and secured thereto between the front and back edges, a front member integral with the bottom but free otherwise and having folding ends adapted to wedge in between the ends of the bottom and back, and a box top integral with the back and having integral ends and an integral front strip which strip is rigidly secured to the end members of the top, substantially as set forth.

2. A folding blank box including a bottom with integral upwardly extending ends with their front edges inclined rearwardly and upwardly, a back integral with the bottom and rigidly secured thereto with integral end members overlapping the ends from the bottom and secured thereto about midway between the front and back edges thereof, a front member integral with the bottom member but otherwise free and having folding ends adapted to wedge in between the ends of the bottom and back so that said front member will engage the inclined front edges of the ends of the bottom member, and a box top integral with the back and having integral ends and an integral front strip, which strip has extensions overlapping the ends of the top and secured thereto so that the front strip will be inclined in substantial alignment with, but adapted to overlap the front member of the box, whereby the front of the box is inclined with the bottom of the box wider than the top thereof, substantially as set forth.

In witness whereof, I have hereunto affixed my signature.

GEORGE A. BELL.
